UNITED STATES PATENT OFFICE.

HARRY MINTZ, OF BOSTON, MASSACHUSETTS.

FOLDING FRAME.

1,385,021.

Specification of Letters Patent. Patented July 19, 1921.

Application filed June 3, 1920. Serial No. 386,333.

To all whom it may concern:

Be it known that I, HARRY MINTZ, a citizen of the United States of America, and resident of Boston, in the county of Suffolk 5 and State of Massachusetts, have invented new and useful Improvements in Folding Frames, of which the following is a specification.

This invention relates to folding frames 10 of that type commonly employed for hammock supports and has for one object the provision of such a frame in which the various members are so connected as to permit of folding such frame into a compact 15 bundle for transportation or storage without necessitating the removal of screws or bolts, and which at the same time affords a rigid and substantial support when in use.

A further object of the invention is to 20 provide such a support which shall be of simple and cheap construction and which requires the minimum of effort to set up or knock down.

In accordance with the present invention 25 the above desirable features may be fully realized, one arrangement of parts for attaining the objects hereinbefore referred to being illustrated in the accompanying drawings in which,—

30 Figure 1 is a perspective view showing the frame in position for use;

Fig. 2 is a side elevation of the frame in collapsed condition;

Fig. 3 is a partial end elevation showing 35 the upper portion of the frame to enlarged scale, and illustrating a bracket for connecting certain of the frame members;

Fig. 4 is a side elevation of the parts shown in Fig. 3;

40 Fig. 5 is a plan view; and

Fig. 6 is a side elevation showing details of a self-locking folding brace employed for securing the frame parts in extended position.

45 Referring to the drawings, 1 indicates a transversely extending supporting bar which preferably comprises an open ended metal tube, although it is to be understood that any equivalent material or shape might be 50 substituted therefor. Associated with said supporting bar 1 are pairs of legs 2, 3; 4, 5, respectively, said legs as herein shown being of tubular formation and having their upper extremities flattened to facilitate connection to the bar 1. These legs may, if desired, be made of ordinary piping, although

if more convenient wooden bars might be employed. 6 is a bracket, of which one is fixedly secured to each extremity of the bar 1, said bracket comprising a central portion 60 7 herein shown as substantially flat and which lies in engagement with the surface of the bar 1. Passing through the portion 7 of the bracket and through the bar 1 are suitable securing means such, for example, 65 as rivets 8, 9, although any equivalent means may be utilized for this purpose.

As herein shown, the rivet 9 extends above the upper surface of the bar 1, where it is provided with a lug or button 10 by 70 means of which a canopy may, if desired, be positioned upon the top of the bar 1. The bracket 6 is herein shown as of sheet metal construction, although it is evident that other modes of forming this bracket 75 may be employed if desired.

Extending downwardly from the lateral edges of the central part 7 of the bracket are ears 11, 12, which diverge from each other making substantially equal angles with the 80 surface of the central portion 7 of the bracket. 13 is a flap up-turned from the free edge of the central portion 7 of the bracket, said flap being designed to cover the open end of the tubular supporting bar 85 1 when the bracket is in position thereon, thus serving to exclude moisture and dirt from the interior of the bar 1 whereby rapid corrosion of the same is obviated.

Fixedly secured within suitable openings 90 in the ears 11—12, respectively, is a pin 14 herein shown as a rivet, headed over upon the outside surfaces of the respective ears. As clearly shown in Fig. 3, the upper ends of the legs may be flattened to form portions 95 15, 16, said portions lying closely against the inner surfaces of the ears 11, 12, respectively, and being pivoted to swing upon the pin 14. Between the adjacent surfaces of the portions 15 and 16 of the legs is placed 100 a spacer member 17 which preferably takes the form of a sleeve mounted upon the pin 14 and provided at its ends with beveled surfaces 18, 19, which bear against the adjacent faces of the parts 15, 16. The angle 105 of the beveled portions 18, 19 of sleeve 17 is such that at their points of contact with the parts 15, 16, they are substantially parallel thereto.

20 is one of a set of folding braces, one of 110 said braces being associated with each of the several legs, said braces being pivotally at-

tached as at 21 to the bar 1 and at 22 to a leg, such pivotal attachment being of a permanent character. 23 indicates one of the similar braces arranged between adjacent legs 2, 3, 4, 5, respectively, and having its extremities permanently and pivotally connected to the respective legs. As seen in Figs. 5 and 6 the braces 20 and 23, which are in general, of like construction, each 10 comprises parts 24, 25 pivoted as at 26 at their meeting extremities whereby they are permitted to fold one upon the other.

These braces are of a self-locking construction such that when straightened out 15 and in operative position they are not readily collapsed and can only be collapsed in one direction. For securing this result the brace member 25 may be provided with a slot 27 extending downwardly from its upper edge 20 and the brace member 24 may have at its extremity a tongue 28 bent at right-angles to the main part thereof, said tongue 28 being of substantially the same depth as the notch 27 and arranged to seat therein. Secured at suitable points in the bar 1 are 25 staples or eye-bolts 29 through which may be passed hook members such as 30 by means of which a hammock or other device may be readily swung from the supporting bar 1.

30 As shown in Fig. 1, the device is in its position of use and is adapted to have a hammock swung from the bar 1, the several parts of the frame being held in rigid relation by means of the braces 20, 23, and the brackets 35 6. When it is desired to collapse the frame for transportation or storage, it is only necessary to break the joints in the braces 20, 23 and to swing the legs about the pivot pins 14, the legs swinging severally in planes 40 parallel to their adjacent supporting bracket ears, until the legs are brought in position to lie in a plane substantially parallel with the bar 1, as indicated in Fig. 2. In this position the frame takes the form of a compact bundle having no upstanding parts to 45 interfere with its ready transportation, while at the same time it is capable of being expanded and set up in position for use with the minimum of time and effort, requiring 50 the use of no tools for this purpose and having no detachable parts, which may become lost or mislaid during transportation.

Having thus described the preferred form of the invention, what I claim is:

55 1. A folding frame comprising in combination a transversely extending hammock support, a bracket fixedly secured to said support and having an angularly disposed ear, a leg member permanently and pivotally secured to said ear and constructed and arranged to swing in a plane substantially parallel to the axis of the support and a foldable brace having its opposite extremities pivotally secured to said support and 60 leg, respectively.

2. A frame of the class described, having in combination a hammock supporting bar, a bracket fixedly secured to said bar, said bracket having angularly disposed ears, a leg pivotally secured to each of said ears, and swingable in a plane substantially parallel to the axis of the bar and collapsible braces each of which has its opposite extremities permanently secured to the bar and to a leg, respectively. 75

3. In combination with a hammock supporting frame member, a bracket having a central portion, laterally and downwardly inclined substantially flat ears extending from said central portion, a member projecting at substantially right angles to said central portion, and a leg pivotally secured to each of said ears to swing in a plane substantially parallel thereto. 80

4. In a folding frame, in combination a bracket having a central portion and laterally extending ears inclined relatively to said central portion, a pivot member extending between said ears and substantially parallel to said central portion of the bracket, frame members swingingly mounted upon said pivot member to turn in planes substantially parallel to the respective ears and means for holding said frame members substantially in contact with said ears. 90

5. In combination, in a folding frame, a bracket having an attaching portion and a pair of ears equally diverging from said attaching portion, frame members pivotally mounted to swing relatively to the respective ears and in planes substantially parallel thereto, and spacing means interposed between said members for holding them in proper operative position. 100

6. In a folding frame, in combination a connecting bracket having divergently arranged downwardly directed ears, a pivot pin secured in openings in said ears, a pair of frame members pivotally supported on said pin, and a spacing sleeve mounted upon said pin between said frame members. 105

7. A folding frame comprising a tubular supporting bar, a bracket fixed adjacent each extremity thereof, said brackets each comprising a pair of divergently arranged ears, a tubular leg pivotally secured to each of said ears to swing in the respective planes thereof, folding braces for each leg having one of their extremities secured to their respective legs and having their opposite extremities pivotally and permanently connected to said bar, and a folding brace connecting the legs of each pair. 115

8. In a folding frame of the class described, a supporting bar provided with hammock attaching hooks, pairs of legs pivotally and permanently secured to said bar, the respective legs of a pair being divergently arranged, and self-locking means for maintaining said legs in normal relation to 120 125 130

said bar, the pivotal connection of said legs to the bar being constructed and arranged to permit said legs to be swung into planes substantially parallel to said bar upon 5 proper manipulation of said locking means.

9. In a folding frame, in combination a bracket member having a central attaching portion and a pair of ears diverging therefrom, a fixed pivot pin arranged substantially parallel to said central portion and engaging openings in the respective ears, a

pair of tubular leg members having their ends flattened and pivotally supported upon said pin and a spacer sleeve mounted upon said pin between the flattened ears of said 15 leg members, said sleeve having its ends beveled to provide contact elements parallel to those of the adjacent ears.

Signed by me at Boston, Massachusetts, this fourteenth day of May 1920.

HARRY MINTZ.
